(57) **CLAIM**

We claim the ornamental design for a telephone handset, as shown and described.

DESCRIPTION

FIG. 1 is a top perspective view of a telephone handset of the present invention;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof;

FIG. 8 is a bottom view thereof; and,

FIG. 9 is a top perspective view thereof shown in an opened position.

The rear edges of the claimed surfaces, shown open and without a clear boundary in FIGS. 1, 2, 6, and 9, continue up to a non-shown line formed by respectively connecting the ends of the two sets of solid lines that define the top and bottom portions of the claimed design.

The broken line showing of the remainder of the telephone handset is for illustrative purposes only and forms no part of the claimed design.
